Primary Examiner — Anhdao Doan(74) *Attorney, Agent, or Firm* — Wood, Herron & Evans, LLP(57) **CLAIM**

The ornamental design for a recirculating bath, as shown and described.

DESCRIPTION

FIG. 1 is a top right isometric view of our new recirculating bath design;

FIG. 2 is a top left isometric view thereof;

FIG. 3 is a bottom left isometric view thereof;

FIG. 4 is a bottom right isometric view thereof;

FIG. 5 is a front elevational view thereof;

FIG. 6 is a rear elevational view thereof;

FIG. 7 is a right side elevational view thereof, a left side elevational view is a mirror image of FIG. 7; and,

FIG. 8 is a top plan view thereof.

The features of the recirculating bath shown in broken dash lines which define the bounds of the claimed design are for illustrative purposes only and form no part of the claimed design.
